(57) **CLAIM**

The ornamental design for an information display terminal, as shown and described.

DESCRIPTION

FIG. 1 is a front, right side, top perspective view of an information display terminal showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a reference perspective view thereof, showing a state in which a panel part is detached; and,

FIG. 9 is a reference top plan view thereof, showing a transparent part by diagonal lines.

The broken lines shown in the figures represent portions of the information display terminal that form no part of the claimed design.
